CLAIM

The ornamental design for a rotating collectable card file, as shown.

DESCRIPTION

FIG. 1 is a perspective view of a rotating collectable card file showing our new design;

FIG. 2 is a front elevation thereof;

FIG. 3 is a rear elevation thereof;

FIG. 4 is a right side elevation thereof;

FIG. 5 is a left side elevation thereof;

FIG. 6 is a top plan view thereof;

FIG. 7 is a bottom plan view thereof; and,

FIG. 8 is a cross-sectional inside view drawn along line 8—8 of FIG. 4.
